(57) **CLAIM**

The ornamental design for an automatic turning mattress, as shown and described.

DESCRIPTION

FIG. 1 is a top, front and right side perspective view of an automatic turning mattress showing my new design;

FIG. 2 is a top plan view thereof;

FIG. 3 is a bottom plan view thereof;

FIG. 4 is a right side view thereof;

FIG. 5 is a left side view thereof;

FIG. 6 is a rear elevational view thereof;

FIG. 7 is a front elevational view thereof;

FIG. 8 is a top, front and right side perspective view of the automatic turning mattress in a state of use, showing an airbag inflated on the left side;

FIG. 9 is a top, front and right side perspective view of the automatic turning mattress in another state of use, showing an airbag inflated on the right side;

FIG. 10 is a bottom, front and left side perspective view of the automatic turning mattress; and,

FIG. 11 is an enlarged view of portion 11 in FIG. 1.

The broken lines in the drawings illustrate portions of the automatic turning mattress which form no part of the claimed design.

The dot-dot broken lines in FIGS. 1 and 11 illustrate the boundaries of the enlarged view which form no part of the claimed design.
